CONE BARLOW AND EDWARD RICHARD CLAPP, OF DONNACONA, QUEBEC, CANADA.

LAYING ROLL.

Application filed May 13, 1924, Serial No. 712,959, and in Canada January 17, 1924.

This invention relates to an improved mechanism or attachment adapted to be incorporated in or affixed to a machine which makes a commodity in web or sheet form, 5 such for example, as a web or sheet of paper.

In particular, the invention relates to the provision of novel means to cooperate with certain parts of machines, of the class to which reference has been made, to produce 10 greater uniformity of web structure and consequently a web or sheet of much greater strength than has heretofore been produced. It has been found that when this novel means or attachment has been incorporated in a 15 paper making machine there are many advantageous results derived in the operation of the machine and in the quality of the product produced. In operating the machine it is found that the resulting sheet be- 20 comes somewhat more hardened and compact than heretofore, and one of the benefits of this result is that it permits the machine to be run or operated at a desired speed with greater operating efficiency. Also, that there 25 results an increase in intensity in the vacuum (as will be later described) which permits the extraction of a greater amount of water from the paper sheet at an advantageous point of its travel through the machine. A 30 particular advantage of the use of this attachment is that the final sheet of paper issuing from the paper machine has a much higher finish than has heretofore been possible to obtain on a machine not provided 35 with our improved attachment. Other advantages, as will hereinafter appear, flow from the use of the present invention.

While for the purpose of illustration the invention will hereinafter be described as 40 applied to paper-making machines, it should be understood that the invention is not limited in its use to such machines but that it may be applied to other machines in which a commodity in web or sheet form is manu- 45 factured or is operated upon.

In practice, in the manufacture of paper, the desired mixture of water and wood fibres flows, as is well known in the art, from a suitable source of supply to a moving Four- 50 drinier wire or screen through which the water may be drained by gravity or be drawn

by suction, thereby causing the fibres to interengage and knit with one another to form the web or sheet of paper. From the wire or screen the web passes to endless felt belts 55 and through sets or batteries of pressing rollers and heating or drying rollers to emerge as paper to be used for various purposes, as, for example, newspapers, books, and the like. As is well known in the paper manufac- 60 turing art, the felt belts pass between the pressing rollers, and that the pressing rollers are so arranged in series that they are known as the first press, second press, third press, etc. 65

In the operation of a paper making machine, as the water drains through the Fourdrinier wire, the wood fibres become more closely associated and commingle and interengage to form the web or sheet. In many 70 instances it is desirable to provide at one or more places near the wire suitable positively acting agencies to assist in removing the desired amount of water from the fibres, and for this purpose there is preferably pro- 75 vided suction or vacuum means. In the paper machines as at present constructed one of these suction devices is suitably mounted in the couch roll around which the endless Fourdrinier wire passes as the sheet 80 leaves the wire to pass to another part of the machine. Other suction devices if desired may be located at different positions under the wire. 85

It has been found from experience that the suction is very advantageous in withdrawing the water, but it is also found that it acts to disturb the normal interengagement or knitted condition of the fibres for the reason that the suction draws the fibres toward the openings in the wire or screen, thus bunching the fibres and up-ending some of them. The resulting sheet of paper is found to be woolly in nature, weak in strength and non-uniform in structure 95 instead of a smoothly knit, strong, fibrous structure.

The main object of this invention is to provide means for preventing distortion or disturbance of the elements in a web or sheet 100 being manufactured or treated, and as relating to paper-making machines, is to pro-

vide a novel and improved apparatus or attachment to cause the wood-fibres to be maintained in their proper distributed relation while the excess liquid or water is being removed by suction.

As incorporated in a paper-making machine, the invention comprises a device to cooperate with the Fourdrinier screen or wire, at a desired position or with the suction couch roll to lay down and press together the wood fibres to a sufficient extent to prevent disturbance thereof by the effect of a suction device. Consequently, a paper sheet of greater uniformity and finish is produced.

By the production of an efficient web or sheet of paper having qualities of strength and uniformity of structure, there flows numerous advantages among which are the following: The paper sheet has a much higher finish than heretofore obtainable thereby making it more suitable for writing and printing purposes. The intensity of the suction or vacuum is increased thereby withdrawing the water more completely from the web. Another and great advantage is that the machine may be run at desired speed with greater operating efficiency thereby increasing the efficient production of the machine. A further advantage is that there is a hardening of the sheet, which automatically results when there is an evenness or uniformity of web structure.

Inasmuch as the invention is not restricted to use alone in paper-making machines, this invention may be considered broadly as having for one of its objects the provision of such a new and useful apparatus or attachment as will cause the elements or ingredients in a web or sheet to be laid down or pressed together in such pre-determined relationship that the relationship will be substantially maintained while the parts of the web or sheet are being acted upon by outside agencies.

A preferred form of application of this invention is illustrated in the accompanying drawings, wherein:

Figure 1 is a top plan view showing the invention applied to so much of a paper-making machine as is necessary for the purpose of illustration.

Fig. 2 is an end elevation of the structure shown in Fig. 1, and

Fig. 3 is a view in cross-section taken along the line 3-3 in Fig. 1.

As herein disclosed, an endless Fourdrinier screen or wire 10 passes around a couch roll 11 having a perforated shell 12, and the web or sheet of paper passes beneath a dance roll 13 to the felts, drying cylinders, pressing rolls and other instrumentalities used in completing the manufacture of the paper. The dance roll 13 serves to equalize the tension exerted on the

paper web 14 as it is drawn from the wire 10 while the latter passes downwardly around the couch roll 11. Inasmuch as the structure or frame supporting the couch roll and Fourdrinier wire at the delivery end of the latter may be of a form heretofore in use, such structure is not described in detail. For convenience, however, this structure or frame is designated in general by 15.

To withdraw as much water as is possible from the web before it passes from the couch roll 11, provision may be made of suitable suction means comprising a suction chamber 16 extending the length of the couch roll and having two walls 17 extending to the inner surface of the perforated shell 12 and having in grooves in their edges suitable packing strips 18 engaging the inner surface of the shell to limit the area of the suction field and therefore render the suction more effective. The water and other matter drawn into the couch roll 11 by the suction passes out of the suction chamber through a suitable pipe 19.

Heretofore, the newly-formed paper web has in passing over the mouth of the suction chamber 17 been subjected to such disturbance of fibre structure or formation by the drawing of the fibres into groups at the openings in the perforated shell 12, that the resulting fibrous paper web 14 assumes a woolly character instead of the smoothly knitted fibrous structure desired. As a result of such suction action the web is so weakened that it is liable to breakage as it is drawn from the couch roll 11 under the dance roll 13 which, for the purpose of equalizing the tension of the web, is journaled in bearing blocks 20 and slidably in brackets 21 projecting from the frame 15.

By employing our improved attachment the fibre structure is sufficiently set or pressed together and the voids in the web or sheet structure are sufficiently sealed to prevent distortion or grouping of the fibres when the suction agency becomes effective. Thus we are enabled to obtain the smoothly knitted fibrous structure so much desired. With the voids in the sheet thus substantially sealed, it is found that the intensity of the vacuum automatically increases and more water is withdrawn from the sheet.

According to one form of the invention, the above-mentioned injurious defects in the paper web are avoided by the use of a fibre-laying roll 22 which cooperates with the wire 10 and couch roll 11 adjacent the wall 17 of the suction chamber which is first reached by the paper web 14 in its movement through the machine. It has been found that if a slight pressure is brought to bear on the paper web just at the point where the suction action of the couch roll begins to become effective, the fibre structure becomes

sufficiently firmly set or pressed together and disturbance of the fibre structure by the action of the vacuum or suction is prevented.

Preferably the roll 22 is of iron usually covered by soft rubber of about 120 plas-
tometer density and is so mounted in this instance as to be rotatable by direct contact with the wire 10 and paper web 14. From experiments and operating experience 10 we find that thoroughly satisfactory results are obtained when the line of such rolling contact is about one inch inside the forward limit of the suction chamber at the left in Figure 3.

15 The fibre-laying roll 22 is suitably journaled in bearing blocks 23 slidable in frames 24 to and from the couch roll 11 and the position of the roll 22 is determined by screws 25 threaded into the blocks 23 and 20 journaled in place 26 in which they are held against downward movement by collars 27 which may be integral with bevel gears 28. Said gears 28 mesh with other bevel gears on a shaft 29 journaled in ears 30 project-
25 ing upwardly from the plates 26. Mounted on one end of the shaft 29 is a hand wheel 31 by which the shaft 29 may be turned to raise or lower both ends of the roll 22 at the same time and in equal relation. By 30 virtue of this arrangement the position of the roll 22 on the wire and couch roll may be varied as desired.

To prevent adherence of any paper fibres to the fibre laying roll 22, provision is made 35 of a shower pipe 32 supported on the brackets 33 and having at short intervals spray nozzles 34 from which a fine water spray may play on the surface of the fibre-laying roll. A deflecting plate 35 running the entire length of the roll and supported by clips 36 from the shaft 29 serves to deflect and concentrate the spray on the surface of the roll 22 and to prevent the spray from coming into contact with the dance roll 13 and 40 the web 14 as it leaves the suction couch roll and is guided by the dance roll to the first felt.

It will, therefore, be seen from the foregoing description of our improved device 50 or attachment, that it is simple in construction and operation, and that the employment of the device produces many advantageous results. One of the main results or benefits 55 accruing is the improved quality of paper due to the improved fibre structure or formation of the paper web, which increases the strength of paper and increases the finish thereof. A further benefit is that there is an increase in the efficiency of safe 60 running of a paper machine by reason of which there is obtainable an increase in the vacuum intensity, elimination of crumbs on the first press; the crumbs being loose fibres that have not been properly interengaged 65 with the other fibres, and the laying roll

presses down any small lumps or coagulations of fibres which have heretofore been the cause of many of the breaks of the paper web on the first press or in other parts of the machine.

As has heretofore been noted the paper sheet passes from the dance roll to heating and pressing rolls. The first two rolls between which the sheet passes after leaving the dance roll 13, constitute what is known 70 as the first press. It is desirable that the sheet of paper as it passes into the first press shall be, in order to prevent buckling and other undesirable troubles, of about twelve 75 percent dryness. To obtain this condition, various devices have been provided. One of the most successfully operating devices for this purpose, being the suction chamber or box mounted in the couch roll. This device alone, however, does not at all times 80 operate successfully to extract sufficient amount of water so that the sheet will be of proper dryness when it passes in the first press.

By incorporating our improved attach- 90 ment in the paper making machine at the preferred position, i. e., above the suction box located in the couch roll, it has been found that there has been no trouble in bringing the paper sheet to the proper dry- 95 ness before it enters the first press.

Flowing from the use of our improved attachment as has heretofore been stated, the intensity of the vacuum in the couch roll 100 materially increases. For this reason the vacuum or suction draws from the paper sheet a much larger quality of water. This of course, being due to the fact that the fibres are maintained in their desired even 105 distribution and intermingled condition, thereby substantially eliminating the voids or openings through which air has heretofore been drawn. The voids or openings being formed as heretofore noted, by the action of the vacuum in drawing the fibres 110 to the openings in the Fourdrinier wire. In many instances, it has been found that when our improved device has been adjusted in position that the vacuum has risen from twelve inches to fifteen inches. From this 115 automatic increase in the vacuum intensity it will readily be seen that by the removal of the proper amount of water, the sheet is quickly brought to the desired percentage of dryness.

While it has herein been stated that the fibre-laying roll 20, may be positioned at any desired place along the Fourdrinier wire, and that the preferred position of this fibre-laying roll is over the suction box 125 mounted in the couch roll, it is to be understood that more than one of the fibre-laying rolls may be employed if desired. As for instance one may be placed near one of the forward suction boxes and another may be 130

placed over the suction box mounted in the couch roll. The advantages of these rolls being that they so lay the fibres that the action of the vacuum or suction will not disturb the proper relation of the fibres.

In the operation of the ordinary paper making machine it is necessary that adjustments of the positions of the suction box in the couch roll and of the heating and 10 pressing rolls be made at short intervals of time. If these adjustments are not made, it is found that breaks in the paper sheet occur at frequent intervals and that the resulting sheet of paper is not of good quality. 15 By incorporating one of our improved fibre-laying rolls in the preferred position over the suction box in the couch roll, it has been found that the adjustments of this suction box to take care of the quick wear of the packing strips 18 does not have to be made so often. By reason of the increase in strength 20 of the paper sheet resulting from the use of our improved fibre-laying roll we find that the adjustments of the heating and pressing 25 rollers do not have to be so closely watched.

By reason of these advantages it will be noted that there is a greater latitude in the safe running of the paper machine while at the same time providing a much higher 30 grade or quality of paper. It will be seen from the foregoing that when our improved device is incorporated in a paper machine that there is obtained a much higher operating efficiency of a machine than has heretofore been possible.

It will be understood that while we have herein described in detail a particular embodiment of our invention for purposes of full disclosure, and some detailed features, 40 which we are specifically claiming for a special advantage, many changes and modifications may be made in the particular construction and arrangement of parts without departing from the broad scope of our invention which is outlined in the subjoined claims.

Having thus described our invention, we claim:

1. In a machine for the manufacture of a web of fibrous material, the combination of 50 a suction device to act on said web, a screen for supporting the web as it passes said suction device, and means positioned to act on said web substantially as it enters the field of action of the suction device to set the fibres of the web in order to prevent distortion thereof by the suction device.

2. In a machine for manufacturing a web 60 of fibrous material, the combination with means to pass a current of air through the web as the latter passes such means in its movement through the machine, means to support the web against such current of air, and means acting on said web substantially 65 at the beginning of the field of action of

the air-current passing means to set the fibrous structure to prevent changes of position of the fibres in the material by the air current.

3. In a paper-making machine having a 70 Fourdrinier wire therein, the combination with such a traveling wire or screen on which a paper web is formed, of a perforated couch roll around which the wire passes at its delivery end, and a suction chamber 75 having walls contacting with the inner face of said couch roll to determine a suction field at the periphery of said couch roll; of a fibre-laying roll positioned to engage the web just inside the edge of the suction 80 field to so set the fibres of the web as to prevent disturbance of the fibrous formation by the suction, and means to maintain the fibre-laying roll in clean condition to assure efficient action thereof. 85

4. In a paper-making machine having a Fourdrinier wire therein, the combination with such a traveling wire or screen on which a paper web is formed, a perforated couch roll around which the wire passes 90 at its delivery end, and a suction chamber having walls contacting with the inner face of said couch roll to determine a suction field at the periphery of said couch roll; of a fibre-laying roll positioned to engage the web just inside the edge of the suction 95 field to so set the fibres of the web as to prevent disturbance of the fibrous formation by the suction, and a spray device extending along the effective length of said fibre-laying 100 roll to throw a spray of water thereon immediately prior to engagement of the web by the sprayed surface.

5. In a paper making machine having a 105 Fourdrinier type of wire therein, the combination with such a traveling wire or screen on which a paper web is formed, a perforated couch roll around which the wire passes at its delivery end, and a suction chamber having walls contacting with the inner face 110 of said couch roll to determine a suction field at the periphery of said couch roll, of a fibre-laying roll positioned to engage the web just inside the edge of the suction field to so set the fibres of the web as to prevent 115 disturbance of the fibrous formation by the suction, a spray device extending along the effective length of said fibre-laying roll to throw a spray of water thereon immediately prior to engagement of the web by the sprayed surface, and a baffle plate to prevent the passage of water from the spray device over the top of the fibre-laying roll. 120

6. In a paper making machine having a 125 Fourdrinier type of wire therein, the combination with a suction couch roll over which passes the Fourdrinier wire with a newly-formed paper web thereon, of means for compacting said web adjacent the beginning of the suction field of said couch roll. 130

7. In a paper making machine having a comprising a roll having a cover of soft Fourdrinier wire therein, the combination rubber.
with a suction couch roll over which passes the Fourdrinier wire with a newly-formed
5 paper web thereon, of means for laying the fibres at the beginning of the suction field of the couch roll, such fibre-laying means
- In testimony whereof we have signed our 10 names to this specification.

CONE BARLOW.
EDWARD R. CLAPP.
